UNITED STATES PATENT OFFICE.

WILLIAM S. HENRY, OF ROCHESTER, NEW YORK, ASSIGNOR TO GENERAL RAILWAY SIGNAL COMPANY, OF ROCHESTER, NEW YORK.

BLOCK SIGNAL SYSTEM FOR RAILROADS.

Application filed July 26, 1926. Serial No. 124,965.

This invention relates to automatic block signal systems for railroads, and more particularly to a system employing semaphore signals and polarized track circuits.

5 In one type of block signal systems, to which the present invention more particularly relates, the clear or proceed and caution indications are given by reversing polarity of the track circuit by a pole changer 10 mechanically operated by a semaphore signal; and in this type of system, if the semaphore signal should be mechanically stuck clear, the pole changer is not operated, and the signal in the rear may indicate proceed 15 when it should indicate caution.

The principal object of the present invention is to provide a circuit arrangement, employing simple and well known devices, to check the operation of each signal and cause 20 the signal in the rear to indicate stop in the event that the signal ahead fails for any reason to assume the stop position. More specifically, it is proposed to include a front contact of the track relay of each block in 25 the track circuit feed for the block next in the rear, and shunt this front contact if the semaphore signal governed by said track relay actually assumes its stop position, so that current is cut off from the track circuit in 30 the block in the rear and the signal thereof put to stop unless the signal ahead actually moves to the stop position and operates the pole changer.

Various other characteristic features and 35 advantages of the invention will be in part apparent to those skilled in the art, and in part pointed out as the description progresses.

The accompanying drawing shows in a 40 simplified and diagrammatic manner, in accordance with established conventions, one embodiment of the invention.

The invention is particularly applicable to a well known type of block signal system 45 employing semaphore signals and polarized track circuits. The track rails 1 are divided by insulated joints 2 into blocks, one block D with the adjacent ends of two other blocks C and E being shown. Disregarding cut 50 sections, intermediate sidings, and the like, the circuit arrangement and equipment for each block may be assumed to be the same; and for convenience corresponding parts for the different blocks are given the same reference characters with distinctive 55

Each block has a polarized track relay T connected across the track rails at the entrance end of that block in conformity with recognized practice. In the particular form of the invention shown, this relay is assumed to be a direct current neutral polar relay; but it should be understood that the invention is applicable as well to systems employing alternating current polarized track circuits. At the entrance to each block is a 60 semaphore signal S, which is controlled in the usual way through a front contact of a neutral armature 3 and normal and reverse contacts of the polar armature 4. Each signal operates a pole changer PC, 70 shown conventionally, this pole changer being mechanically shifted at an intermediate point in the movement of the signal between its caution or 45 degree position and its stop or zero degree position, this point ordinarily being about 43 degrees above the horizontal. Also associated with each signal is a circuit breaker or controller, of the usual construction, which is mechanically operated by the signal. This circuit breaker CB 80 is shown in accordance with established convention, and is adjusted to close its contacts in the zero degree or stop position of the signal.

The track battery 5 is connected to the 85 pole changer PC of the signal at the entrance to the next block in advance. One terminal of the pole changer PC is connected by a wire 6 to one of the track rails at the exit end of the block next in the rear. The other terminal of the pole changer PC is connected by wires 7 and 8, front contact 9 of the track relay and wire 10 to the other track rail of said block. Front contact 9 of the track relay is shunted by a wire 11 and 90 the contacts of the circuit breaker CB.

Normally, when no trains are present, the parts and circuits assume the position shown in the drawing. Each signal S is in the clear position, its pole changer PC is in the 100 normal position supplying current of normal polarity to the track circuit in the rear through the front contact 9 of the track relay T. When a train enters a block, as the block D, the track relay T is shunted and 105 opens its front contacts 3 and 9. The opening of the front contact 3 cuts off current from the signal S, which moves toward its stop position. When the signal S drops below its 45 degree or caution position, the pole 110

changer PC is shifted; and when the signal reaches its horizontal position, the contacts of the circuit breaker CB close, thereby establishing a supply of track circuit current of reverse polarity to the block C in the rear through the shunt around the track relay contact 9 through the circuit breaker contacts and wire 11. If the signal is stuck clear, or for any other reason fails to assume the stop position, the opening of the front contact 9 of the track relay T maintains current cut off from the track circuit of the block in the rear, holding the signal in the rear at stop. When the train in question advances out of the block D, the direction of traffic being from left to right as indicated by the arrow, the track relay T picks up and clears the signal S to the caution position, assuming of course that the signal S for the block E operates properly. This movement of the signal reverses the pole changer PC, and the track circuit current of the normal polarity, supplied to the block C, allowing the signal at the entrance to said block C to clear to the proceed position.

It will be noted that when a train enters a block, as the block D, current to the track circuit of the block C next in the rear is temporarily cut off upon opening of the track relay contact 9 until the contacts of the circuit breaker CB close. This time is relatively short, and is that taken for a semaphore signal to move from its proceed position to the stop position. Ordinarily, the rear end of the train entering the block D will be in the block C, holding the signal for block C at stop, due to the shunting of the track relay for the block C, so that such temporary interruption of track circuit feed is not material. In any event, such interruption merely delays the time of clearing the signal in the rear.

The particular embodiment of the invention shown and described is merely typical and representative; and I desire to have it understood that various modifications and adaptations may be made in the particular construction and arrangement of circuits shown and described without departing from the invention.

What I claim is:

1. In a block signaling system for railroads having tracks divided into blocks, a semaphore at the entrance to each block, a polarized track relay at the entrance end of each block governing said signal, a pole changer mechanically operated by each signal, a source of current, electrical connections between said source of current and the track rails including said pole changer and a front contact of the corresponding track relay for supplying track circuit current to the block next in the rear, and circuit controlling means operated by the signal for shunting said front contact of the corre-

sponding track relay if said signal is in its stop position.

2. A block signaling system for railroads having polarized track circuits comprising, in combination with a polarized track relay for each block, a semaphore signal at the entrance to each block, a pole changer operated by each signal; of a source of current and circuit connections governed by said pole changer for reversing the polarity of track circuit current supplied to the block next in the rear of the corresponding signal, said electrical connections including in multiple a front contact of the track relay of the block corresponding to the signal and said circuit controller of that signal, whereby de-energization of a track relay of a given block will cut off current of the track circuit to the block next in the rear unless the signal for said given block assumes its stop position.

3. In a block signaling system of the type described including polarized track circuits and semaphore signals, a source of track circuit current for each block, a pole changer operated by each signal during its movement from the caution position to the stop position, electrical connections between said current source and the track rails for supplying track circuit current to each block, said electrical connections including a front contact of the track relay of the block next in advance, whereby de-energization of the track relay of a given block cuts off the track circuit current for the block in the rear, and means dependent upon the movement of a given signal to its stop position for supplying said track circuit current to the block in the rear independently of said track relay.

4. In a block signal system of the character described, a block provided with a track relay, a semaphore signal at the entrance to said block, a pole changer operated by said signal and closed in its stop position, and electrical connections between said pole changer, and a track in the rear of said block including a front contact of said track relay.

5. In a block signal system of the character described, including polarized track circuits, the combination with a track circuit and its track relay, a semaphore signal governed by said track relay, a circuit controller operated by the signal and having contacts closed only if said signal is in the stop position, and electrical connections for supplying current to the track circuit next in the rear comprising a front contact of said track relay and the contacts of said circuit controller arranged in multiple.

6. In a block signal system, the combination with a railway track divided into blocks, a track circuit for each block including a track relay, means at the entrance of one block responsive to the condition of

occupancy of that block and the next block in advance having contacts associated therewith for applying track circuit current to the next block in the rear of said one block 5 of a polarity depending upon the condition of said means, a control contact controlled by said means closed when said one block

is occupied and connected in series with the track circuit of the block in the rear, and a contact closed when the track relay of said one block is energized for shunting said control contact. 10

In testimony whereof I affix my signature.
WILLIAM S. HENRY.
